UNITED STATES PATENT OFFICE

FRANK F. MARQUARD, OF CLAIRTON, PENNSYLVANIA

METHOD OF REMOVING NAPHTHALENE FROM SOLVENT NAPHTHA

No Drawing.

Application filed July 1, 1929. Serial No. 375,337.

This invention relates to the purification and recovery of distillates containing resins or resinifying constituents, and more particularly coal tar distillates comprising solvent naphtha containing useful resinous constituents and naphthalene.

An object of the invention is to provide a process by which naphthalene may be removed from the solvent naphtha without polymerizing the resins or resinifying constituents.

Another object of the invention is to provide a solvent naphtha distillate substantially free from naphthalene and containing a quantity of resinifying constituents.

With these and other objects in view, the invention comprises the process and product described in the following specification and claims.

20 In the following description the invention is illustrated as applied to a coal tar distillate or fraction known in the trade as No. 2 crude heavy solvent naphtha. This fraction is obtained from the benzol light oil fraction of 25 coal tar by distilling off first a fraction having a distilling point of 81° C., and consisting principally of benzol, then a fraction at 110.2° C., containing a toluol, and then a fraction ranging from 137 to 140° C., containing xylol, 30 and then a fraction ranging from about 160° C., to 195° C., which forms the No. 2 crude heavy solvent. This fraction also contains the cumeron and indine resins or constituents forming these resins upon polymerization.

35 In the distillation of the coal tar to form the No. 2 crude heavy solvent naphtha, a quantity of naphthalene is carried over with the vapors, the quantity ranging from 1 to 8% of naphthalene. This naphthalene cannot 40 be separated and removed by means of sulfuric acid without, at the same time, polymerizing the resins and thus removing them from the fraction.

In accordance with the present invention the 45 No. 2 crude heavy solvent naphtha containing the resins and naphthalene impurity is mixed with an absorbent petroleum oil known generally as "wash oil" and having a distillation range of from about 230 to 330° C., and containing only a small amount of hydrocarbons

that are easily broken down or decomposed by heat. This type of wash oil is commonly and generally used for absorbing benzol out of the gases obtained from the destructive distillation of coal.

55

The wash oil and crude heavy solvent naphtha are preferably mixed in approximately equal proportions. The mixture is then subjected to distillation and the solvent naphtha is distilled off from the wash oil, which retains the naphthalene. The resins or resinifying constituents of the fraction pass over with the distillate. By selecting a mineral oil or wash oil materially above the boiling point range of the solvent naphtha being treated, the distillation may be readily carried out without a substantial loss of the required solvent naphtha. After distilling off the solvent naphtha and the resins or resinifying products, the wash oil may be used in the usual manner for absorbing a fresh quantity of benzol from the coal distillation gases. The purified distillate is substantially free from naphthalene and contains a large quantity of resins or resinifying products ranging from 30 to 60 per cent. These resins may then be polymerized and removed, leaving a solvent naphtha suitable for paints, etc.

75

Although the invention has been described for the removal of naphthalene from No. 2 crude heavy solvent naphtha, it will be understood that it may be applied generally to distillates containing naphthalene as an impurity and also containing resins or resinifying substances which it is desired to obtain free from naphthalene without polymerizing.

80

85

What I claim is:

1. A process of separating naphthalene from a heavy crude solvent naphtha containing resin constituents and naphthalene which comprises adding a quantity of a hydrocarbon oil having a boiling point materially higher than the boiling point of the heavy crude solvent naphtha being processed to said heavy crude solvent naphtha, and then distilling off the solvent naphtha and resin constituents.

95

2. A process of separating naphthalene from a heavy crude solvent naphtha containing resin constituents and naphthalene which

100

comprises mixing said solvent naphtha being processed with substantially equal proportions of a hydrocarbon oil having a boiling point materially higher than the boiling point of said solvent naphtha being processed, and then distilling off the solvent naphtha and resin constituents.

3. A process of separating naphthalene from a crude solvent naphtha containing resin constituents and naphthalene which comprises mixing said solvent naphtha being processed with a quantity of a hydrocarbon oil having a boiling point materially higher than the boiling point of said solvent naphtha being processed, and then distilling the solvent naphtha and resin constituents from the naphthalene and hydrocarbon oil.

4. A process of separating naphthalene from a crude solvent naphtha recovered from the destructive distillation of coal and containing resin constituents and naphthalene which comprises mixing said solvent naphtha being processed with a quantity of mineral oil having a boiling point materially higher than the boiling point of said solvent naphtha being processed, and then subjecting said mixture to distillation to distil off the solvent naphtha and resin constituents from the mineral oil and naphthalene.

30 In testimony whereof, I have hereunto set my hand.

FRANK F. MARQUARD.
